Fig. 3

Fig. 4

Fig. 5

Fig. 1 is a perspective view of a copy camera, showing my new design with the copy holder in open position;

Fig. 2 is a perspective view thereof with the copy holder in closed position;

Fig. 3 is a side elevational view thereof;

Fig. 4 is a front elevational view thereof; and

Fig. 5 is a top plan view thereof.

The broken line showing of a film holder in Figs. 2, 3 and 5 is for illustrative purposes only.

The dominant features of my new design are shown in solid lines in the drawing.

I claim:

The ornamental design for a copy camera, substantially as shown and described.
